UNITED STATES PATENT OFFICE.

FELIX D. LANGEVIN, OF LOWELL, MASSACHUSETTS, ASSIGNOR TO SACO-Lowell SHOPS, OF BOSTON, MASSACHUSETTS A CORPORATION OF MASSACHUSETTS.

LAP-WINDING MACHINE.

Application filed April 8, 1925. Serial No. 21,482.

This invention relates to lap winding mechanisms, such for example as those used in cotton pickers, evener lappers, and the like.

Mechanisms of this type include a friction let-off usually comprising a brake drum running in contact with a brake shoe or band, the friction so exerted on the brake drum resisting the building up of the lap and consequently controlling the hardness of the lap. The friction between the brake drum and the band may change considerably without the machine attendant becoming aware of that fact, as, for example, due to the absorption of moisture by the lining on the brake band or shoe on warm moist days. Such an increase in resistance often is sufficient to make a very great and objectionable difference in the hardness of the laps. It is, therefore, the chief object of the present invention to devise means for preventing an occurrence of this character. The invention also aims to accomplish this general result by a simple and inexpensive mechanism.

The nature of the invention will be readily understood from the following description when read in connection with the accompanying drawings, and the novel features will be particularly pointed out in the appended claims.

Referring now to the drawings,

Figure 1 is a side elevation of a part of the lap winding mechanism of an evener, picker, or similar machine;

Fig. 2 is a cross sectional view on the line 2—2, Fig. 1;

Fig. 3 is a side view of a special gear shown in Fig. 2; and

Fig. 4 is a cross sectional view on the line 4—4, Fig. 3, showing the gear and a disk which cooperates with it.

Referring first to Figs. 1 and 2, the lap winding rolls are indicated at 2 and 3, these rolls being rotated in a suitable direction to wind the lap 4. The lap is wound on an arbor or spindle 5, and during this operation two racks bear on the opposite ends of the arbor or spindle. One of these racks is shown at 6 in Figs. 1 and 2, and a part of the other rack is shown at 7 in Fig. 2. Each rack is provided with a head at its upper end in which rolls 8 and 9 are mounted to bear on the end of the spindle 5. Both

racks are guided vertically in the machine frame.

The toothed portions of these racks mesh with pinions 10 and 11, respectively, Fig. 2, which are secured to a horizontal rack shaft 12, so that as the lap 4 increases gradually in diameter the racks will be lifted and thus rotate the shaft 12. Keyed, or otherwise secured, rigidly on the shaft 12 is a disk 14, Fig. 2, and mounted immediately beside this disk but free on the shaft 12 is a gear 15. A wooden shearing pin 16 connects this disk and the gear so that the disk drives the gear through the pin 16. The gear 15 drives a pinion 17 mounted to rotate freely on a counter shaft 18, this pinion being formed integral with, or secured to, a gear 19 meshing with a gear 20 on the shaft 12. A brake drum 21 is secured fast to the pinion 20 or is formed integral with it, and the periphery of this drum is engaged by a brake shoe 22 secured on a brake lever 23 which is pivoted on the shaft 18. A treadle 24 is formed at the forward end of this lever and a weight 25 is mounted for slidable adjustment on the rearward end of the lever. The shaft 12 is provided with a hand wheel 26 by means of which it may be rotated manually.

It will now be understood that as the shaft 12 is rotated slowly by the gradual increase in diameter of the lap 4 as it builds up, this rotary motion will be transmitted through the gearing above described to the brake drum 21, thus rotating this drum against the friction of the brake shoe 22. The resistance so applied to the building up of the lap can be adjusted by moving the weight 25 backward or forward. If now the friction applied by the brake shoe should become excessive for any reason, as, for example, due to the absorption of atmospheric moisture by the shoe, the pin 16 will shear off when this resistance reaches a predetermined value, and thus will render the connections between the lap and the brake drum inoperative. The attendant upon observing that the operation of the let-off mechanism had been interrupted would know at once that the brake mechanism was set up too hard and would adjust the weight 25 inwardly before replacing the pin 16 and starting up the machine again.

It will be observed that the power trans-

mitted through the shearing pin 16 to the disk 14 will depend upon the diameter of pin and the material of which it is made. Since the adjustment of the let-off mechanism will be varied to suit the character and requirements of the work, it is evident that it is desirable to use shearing pins of different sizes or shearing resistances. Accordingly, I have provided the disk 14 and gear 15 with three holes, as shown in Fig. 3, these holes being indicated, respectively, at 28, 29 and 30. They are made slightly different in size so that they will take shearing pins of different sizes. While I prefer to use shearing pins made of wood, it is within the scope of the invention to use other materials for this purpose.

It will now be evident that the mechanism provided by this invention automatically prevents an excessive increase in the resistance imposed by the let-off mechanism on the building of the lap so that it is impossible to wind laps of a hardness greater than that for which the shearing pin connecting the gear 15 and disk 14 is selected. The mechanism adds but a trifling increase to the expense of manufacture of the machine, and ordinarily requires absolutely no care or attention on the part of the workman or machine attendant.

Having thus described my invention, what I desire to claim as new is:

1. In a lap winding machine, the combination of lap winding means, a friction let-off mechanism including a brake drum and a brake shoe bearing against said drum, said mechanism also including connections arranged to be operated by the gradual increase in diameter of the lap for rotating said drum, and automatic means for rendering said

connections inoperative when the friction on said drums becomes excessive, said means being selective to permit a variation in the resistance at which it will interrupt the operation of said connections. 45

2. In a lap winding machine, the combination of lap winding rolls, a lap spindle, racks arranged to bear on opposite ends of said spindle to press the lap against said rolls, a rack shaft, pinions secured on said shaft and arranged to be rotated by said racks, a rotary brake drum, a brake shoe bearing against said drum, and connections between said drum and said shaft for transmitting the rotation of the shaft to the drum, 50 said connections including a gear freely rotatable on said shaft, a disk immediately beside said gear and fast on said shaft, and a shearing pin connecting said disk and gear and serving to transmit motion from said 55 disk to said gear.

3. In a lap winding machine, the combination of lap winding rolls, a lap spindle, racks arranged to bear on opposite ends of said spindle to press the lap against said 60 rolls, a rack shaft, pinions secured on said shaft and arranged to be rotated by said racks, a rotary brake drum, a brake shoe bearing against said drum, and connections between said drum and said shaft for transmitting the rotation of the shaft to the drum, 65 said connections including a gear, a disk mounted beside said gear, and a shearing pin connecting said disk and gear and transmitting motion from one of said parts to the 70 other, said disk and gear having a plurality of holes adapted to register with each other to receive shearing pins of different sizes. 75

FELIX D. LANGEVIN.
